(57) **CLAIM**

The ornamental design for a crown shaped gummy, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front, top and left side perspective view of a first embodiment of a crown shaped gummy;

FIG. 2 is a front view thereof;

FIG. 3 is a left side view thereof;

FIG. 4 is a rear view thereof;

FIG. 5 is a right side view thereof;

FIG. 6 is a top view thereof;

FIG. 7 is a bottom view thereof;

FIG. 8 is a front, top and left side perspective view of a second embodiment of a crown shaped gummy;

FIG. 9 is a front view thereof;

FIG. 10 is a left side view thereof;

FIG. 11 is a rear view thereof;

FIG. 12 is a right side view thereof;

FIG. 13 is a top view thereof;

FIG. 14 is a bottom view thereof;

FIG. 15 is front view of a third embodiment of a crown shaped gummy;

FIG. 16 is a right side perspective view thereof;

FIG. 17 is a left side view thereof;

FIG. 18 is a rear view thereof;

FIG. 19 is a top perspective view thereof; and,

FIG. 20 is a bottom perspective view thereof.
